UNITED STATES PATENT OFFICE

2,210,812

FUEL MIXING DEVICE

Fredrick Koch, Detroit, Mich.

Application March 10, 1939, Serial No. 261,080

2 Claims. (Cl. 48—180)

My invention relates to internal combustion engines, and has among its objects and advantages the provision of an improved fuel mixer.

An object of my invention is to provide novel means for introducing additional air into the fuel mixture produced by the carburetor of the engine. I provide means for introducing a constant but variable supply of air to the carburetor mixture, in addition to providing novel means for introducing a supplementary volume of air in proportion to the extent to which the throttle valve is opened. The supplementary air introducing means are operatively associated with the throttle valve so as to be simultaneously actuated therewith through operation of the throttle valve.

In the accompanying drawing:

Figure 1 is a sectional view of the conduit between the carburetor and the intake manifold of the engine illustrating my invention incorporated therein;

Figure 2 is a sectional view taken substantially along the line 2—2 of Figure 1;

Figure 3 is a sectional view taken substantially along the line 3—3 of Figure 1; and

Figure 4 is a detail view illustrating the manner in which the invention is operatively connected with the throttle valve control.

In the embodiment selected to illustrate my invention, the carburetor is indicated generally at 10 and includes the usual conduit 12 for connection with the intake manifold of the engine. Conduit 12 includes conventional sections 14 and 16 which are flanged at 18 and 20, respectively. In the instant case, sections 14 and 16 are separated sufficiently far to accommodate the mixing unit 22, and the parts are connected into a unitary structure by bolts 24 in the manner of the original connections between the sections 14 and 16.

Unit 22 includes a frame 26 having its outer face 28 contoured to correspond to the outer faces 30 of the flanges 18 and 20, with the frame 26 clamped between the two flanges. I fashion the frame to provide an annular flange 32 which fits snugly inside the section 14, and the frame is provided with an annular groove 34 located so as to provide a wall 36 lending continuity to the conduit defined by the sections 14 and 16. Wall 36 terminates slightly short of the face 38 of the frame 26 to provide accommodation for a flange 40 associated with a ring 42 fitting snugly inside the section 16, with the inner face of the ring lying substantially flush with the inner face of the wall 36 and the flange 32.

Flange 32 includes a bar 44 provided with a

socket 46 for supporting a roller bearing 48 which supports one end of a shaft 50 to which I key a fan 52. The upper end of the shaft 50 lies in a socket 54 carried by a bar 56 formed integrally with the ring 42. I prefer to interpose a roller bearing 58 between the upper end of the shaft 50 and the bottom of the bearing socket 54. To the shaft 50, between the fan 52 and the bar 56, I fixedly connect an arm 60 provided with a plurality of transverse perforations 62 and arranged at a slight angle to the plane of the fan 52, as illustrated in Figure 1.

Wall 36 is provided with a plurality of ports 63 which establish communication between the annular groove 34 and the conduit defined by the sections 14 and 16. I provide the frame 26 with a valve plate 64 pivotally mounted along its upper horizontal edge on a shaft 66. Plate valve 64 is located inside a passage 68 in the frame 26, which passage establishes communication between the annular groove 34 and the atmosphere, assuming that the plate valve 64 is opened.

Diametrically opposite the passage 68 and in the frame 26 I provide a second passage 70 for establishing communication between the annular groove 34 and the atmosphere. I provide the frame with an extension 72 provided with a bore 74 within which I mount a rotary valve 76 slabbed off at 78 so as to open the passage 70 when positioned according to Figure 1. Extension 72 is provided with a slot 80 constituting a continuation of the passage 70. Rotary valve 76 may be adjusted to different positions for variably restricting communication between the annular groove 34 and the atmosphere.

Figure 2 illustrates the specific construction of the rotary valve 76, which valve includes a bearing reach 82 rotatably supported inside one end of the bore 74. The opposite end of the rotary valve includes a bearing reach 84 rotatably supported in the opposite end of the bore. A smaller bore 86 accommodates the short shaft part 88 of the rotary valve, which shaft part is provided with a threaded opening for the reception of a screw 90, the head of which engages the face 92 of the extension 72. Thus the head of the screw and the end 94 of the rotary valve cooperate to restrain the rotary valve from relative longitudinal shifting inside the bore 74.

To the end 96 of the rotary valve I fixedly connect one end of an arm 98, the other end of which is pivotally connected with one end of a link 100 having its opposite end pivotally connected with an arm 102 fixedly related to the

shaft 104 which carries the throttle valve 106. Shaft 104 is provided with the usual arm 108 having its outer end loosely connected with a control rod 110 through the medium of which the throttle valve 106 is adjusted.

In operation, the control illustrated in Figure 4 is such that the rotary valve 76 closes the passage 70 when the valve 106 is in its idling position. As the throttle valve 106 is progressively moved to an open position, the control mechanism of Figure 4 opens the rotary valve 76 in corresponding degrees. Irrespective of the rotary valve 76 the plate valve 64 operates automatically to admit air to the conduit 12. The amount admitted depends upon the degree of suction in the conduit 12. Fan 52 lies in the plane of the ports 63, and the fan has its blades angled in such fashion as to impart rapid rotation thereto in response to the passage of the fuel mixture through the conduit. Fan 52 will be rotated at a rapid rate, and the perforated arm 68 will cooperate with the fan to effectively mix the supplementary air with the carburetor mixture. As the throttle valve 106 is moved toward its open position, rotary valve 76 is automatically opened in proportional degree so as to admit additional air to the carburetor mixture, thus supplementing the automatic plate valve 64.

Without further elaboration, the foregoing will so fully illustrate my invention that others may, by applying current knowledge, readily adapt the same for use under various conditions of service.

I claim:

1. In a carbureted fuel conduit of an internal combustion engine, a rotary mixing element in said conduit mounted for rotation about the axis of the conduit and being rotatably responsive to the fuel mixture passing therethrough, said conduit having an air passage extending circumferentially thereabout, the wall of the conduit being provided with air ports located in the plane of said rotary mixing element for the admission of air to the conduit and for delivery to the rotary mixing element to be mixed with the fuel mixture in the conduit, a suction responsive air control valve communicating with said air passage, and a manually controlled air inlet valve 15 for said air passage.

2. In a carbureted fuel conduit of an internal combustion engine, a rotary mixing element in said conduit mounted for rotation about the axis of the conduit and being rotatably responsive to the fuel mixture passing therethrough, said conduit having an air passage extending circumferentially thereabout, the wall of the conduit being provided with air ports located in the plane of said rotary mixing element for the admission of air to the conduit and for delivery to the rotary mixing element to be mixed with the fuel mixture in the conduit, and a perforated arm 20 fixed to the fan for rotation therewith and extending generally transversely of said conduit. 25

FREDRICK KOCH.
